MENORAH TREE

Roland Auclair, 142 Summit Ave.,
Brookline, Mass. 02146

Filed Sept. 10, 1971, Ser. No. 179,618

Term of patent 14 years

Int. Cl. D11—05

U.S. Cl. D29—1 A

FIG. 1

FIG. 3

FIG. 1 is a perspective view of a menorah tree showing my new design;

FIG. 2 is an enlarged perspective view of one tier of the tree; and

FIG. 3 is an enlarged exploded fragmentary perspective view of the top of the tree.

I claim:

The ornamental design for a menorah tree, as shown.
